UNITED STATES PATENT OFFICE.

DAVID D. MOORE, OF ENFIELD, VIRGINIA.

TOY.

1,342,344.

Specification of Letters Patent.

Patented June 1, 1920.

Application filed February 6, 1920. Serial No. 356,590.

To all whom it may concern:

Be it known that I, DAVID D. MOORE, a citizen of the United States, residing at Enfield, in the county of King William and 5 State of Virginia, have invented new and useful Improvements in Toys, of which the following is a specification.

This invention relates to toys and has for an object the provision of a toy of novel 10 and attractive design, which may be operated to simulate a man catching a fish.

Another object of the invention is the provision of a toy of simple construction and operation and which may be manufactured 15 and sold at a low cost.

Other objects and advantages of the invention will appear as the following description is read in connection with the accompanying drawings.

20 In the drawings,

Figure 1 is a side elevation showing the figure bent forward as in the act of angling for a fish.

Fig. 2 is a similar view with the figure 25 raised and showing by dotted lines the swinging movements of the figure.

Fig. 3 is a plan view with the figure in the position shown in Fig. 1.

Fig. 4 is a similar view with the figure 30 in the position shown in Fig. 2.

Fig. 5 is a longitudinal sectional view.

Fig. 6 is a transverse section.

Fig. 7 is an enlarged view showing the connection between the figure and the 35 plunger.

Referring to the drawings in detail, wherein like characters of reference denote corresponding parts, the reference character 10 designates a base which is of elongated 40 formation and which is provided intermediate its ends with a relatively wide portion 11. The base is grooved longitudinally upon its upper surface as indicated at 12 and operating within this groove is a plunger 45 13. This plunger is provided at one end with an operating knob 14, which also acts as a stop to limit the inward movement of the plunger. The groove 12 is covered for a portion of its length by a platform 15, the 50 latter extending laterally upon each side so as to cover the wide portion 11 of the base.

Pivotal secured at one end of the base is a figure 16, which is shown to represent a man. This connection is effected through 55 the medium of a link 17, having one end pivoted to the base and the opposite end rigidly

secured to the figure 16. Included in this link is a coil spring 18, which permits of a relative pivotal movement between the opposite ends of the link. Connected to the link 17 60 at one side of the spring 18 is one end of a link 19, the opposite end of this link being pivotally connected to the adjacent end of the plunger 13. By this means when the plunger is drawn outward the figure will 65 bend in a direction toward the outer end of the plunger and when the plunger is forced inward by a more or less rendered movement the figure will be raised and at the end of this movement will be given a further rear- 70 ward pivotal movement with the spring 18 as a pivot, imparting a sudden backward jerk to the figure. The arms of the figure have secured thereto one end of a rod 20, which represents a fishing rod, while piv- 75 otally connected to the opposite end of the rod is a fish or other object 21. In the sudden backward jerking movement of the figure, the fish, which rests upon the platform when the figure assumes a forwardly 80 bending position, will be suddenly jerked from the platform and a pivotal movement imparted thereto, to simulate the jumping and contortion of a fish as it is jerked from the water.

To further add to the novelty of the device, the wide portion 11 is transversely grooved and secured within the groove upon each side of the plunger 13 is an arm 22. This arm is pivotally mounted as indicated 90 at 23 and has one end secured to the plunger 13. The arms are outwardly bowed or curved and have secured to their extremities inwardly extending hands 24. Thus, when the plunger is pulled outward and the figure 95 bends forward, the hands 24 will come together at the rear of the figure and in the forward movement of the plunger the hands will be separated.

Having described the invention what is 100 claimed is:—

1. A toy embodying a base, a figure pivotally connected thereto, a plunger movable longitudinally of the base and connected to the figure, whereby the latter may be moved upon its pivot, a rod carried by the figure and a fish secured to one end of the rod, whereby when the plunger is operated the figure will be moved to simulate the act of fishing.

2. A toy embodying a base, a figure pivotally connected thereto, a plunger movable

longitudinally of the base and connected to the figure, whereby the latter may be moved upon its pivot, a rod carried by the figure and a fish pivotally connected to one end of the rod, whereby when the plunger is operated the figure will be moved rearward and the fish rotated to simulate the act of fishing.

3. A toy embodying a base, a figure pivotally connected thereto, a plunger movable longitudinally of the base and connected to the figure, whereby the latter may be moved upon its pivot, a flexible connection included in the pivotal connection between the figure and base, a rod carried by the figure and a fish secured to one end of the rod, whereby when the plunger is operated the figure will be moved to simulate the act of fishing.

4. A toy embodying a base, a figure pivotally connected thereto, a plunger movable longitudinally of the base and connected to the figure, whereby the latter may be moved

upon its pivot, an independent pivotal spring joint included in the pivotal connection between the figure and base, a rod carried by the figure and a fish secured to one end of the rod, whereby when the plunger is operated the figure will be moved to simulate the act of fishing.

5. A toy embodying a base, a figure pivotally connected thereto, a plunger movable longitudinally of the base and connected to the figure, whereby the latter may be moved upon its pivot, a rod carried by the figure, a fish secured to one end of the rod, whereby when the plunger is operated the figure will be moved to simulate the act of fishing and a pair of spring arms pivotally secured to the base and connected to the slide and actuated simultaneously with the operation of the figure.

In testimony whereof I affix my signature.

DAVID D. MOORE.
